UNITED STATES PATENT OFFICE.

BENJAMIN S. McCLELLAN, OF CHICAGO, ILLINOIS.

EXPANSION-VALVE.

1,300,182.

Specification of Letters Patent.

Patented Apr. 8, 1919.

Application filed January 4, 1915. Serial No. 351.

To all whom it may concern:

Be it known that I, BENJAMIN S. McCLELLAN, a citizen of the United States, and a resident of the city of Chicago, in the county 5 of Cook and State of Illinois, have invented certain new and useful Improvements in Expansion-Valves; and I do hereby declare that the following is a full, clear, and exact description thereof, reference being had to 10 the accompanying drawings, and to the characters of reference marked thereon, which form a part of this specification.

This invention relates to fluid pressure or 15 expansion valves and more particularly to that type of such valves that are adapted for use in refrigerating systems and designed for controlling the passage of the liquid ammonia or fluid from the high to the low 20 pressure passages of such valves and in which latter passages the liquid ammonia is converted into a gaseous form.

Among the objects of the invention is to 25 improve the construction of valves of the kind referred to, in the several particulars as will hereinafter appear and to provide in particular, a fixed and movable valve member, the latter being provided with a valve stem having an axial or longitudinal fluid 30 passage closed at both ends, there being lateral outlet and inlet ports in the valve stem and opening into said axial fluid passage intermediate the ends thereof. The inlet port when open, allows the liquid ammonia to 35 flow from the high into the low pressure passages of the valve and said inlet port will be completely open, only when the movable valve member has moved to the fullest extent of its movement in a direction completely to open said inlet port and to only 40 partially open said inlet port when the said movable valve member has moved into any position between those occupied when the inlet port is completely closed or opened.

The invention consists further in the matters hereinafter described and more particularly pointed out in the appended claims.

In the accompanying drawings:

Figure 1 is a vertical sectional view of a pressure regulating or expansion valve 50 constructed in accordance with my invention;

Fig. 2 is an enlarged transverse sectional view taken on the broken line 2-2 of Fig. 1;

Fig. 3 is a view in side elevation of the 55 movable valve member of my valve; and

Fig. 4 is a vertical sectional view of another form of said movable valve member.

Referring to the accompanying drawings, illustrating in detail a pressure regulating or expansion valve embodying the features 60 of my invention, 10 indicates the valve casing, which, as shown, comprises two parts 11, and 12, said parts when assembled and connected together forming said valve casing. As illustrated, the part 11 is the uppermost one and the part 12 is the lowermost one, said parts being secured together by clamp or like bolts 13, 13 inserted through registering bolt holes in said parts. Clamp nuts 14, 14 are applied upon the screw-threaded ends of said bolts as shown in Fig. 1. The valve casing part 12 is provided with a centrally disposed annular valve chamber 15 into which open from the sides of the valve casing, one or more fluid passages 16, 17, both being formed in said part 12. As shown, said fluid passages 16, 17 open outwardly through the sides of the valve casing, and each passage is adapted to open into and have communication with a suitable pipe or conduit (not shown) the end of which is inserted into such passage. For the purpose of connecting the pipes or conduits with said fluid passages 16, 17, the walls of the latter are provided with internal 80 screw threads, adapted to receive complementary external screw threads on the end portions of said pipes.

Located within said valve chamber 15, is an endwise or vertically movable valve member 18. Said movable valve member 18 comprises an enlarged circular head 19 and a depending stem 20, the latter having a lower reduced end portion 21. A downwardly facing shoulder 22 is provided intermediate 95 the ends of the valve stem, and said shoulder is formed at the junction of the enlarged upper part of the valve stem with the reduced lower part 21 thereof. As shown, the part 21 of the valve stem is cylindric in 100 form. The bottom wall 12^a of the valve chamber 15 is provided with an upwardly facing surface 23, against which the shoulder seats or contacts when the movable valve member 18 is at the limit of its downward 105 movement. The surface 23 constitutes in effect, a valve seat for the movable valve member 18. Said bottom wall 12^a is provided with a vertical hole or cylindric bore 24, which opens at its upper end through 110

the seat 23 into the valve chamber 15. Said bore 24 opens at its lower end into a fluid passage 25, the latter being formed in said valve casing part 12 and opening outwardly 5 through the bottom of the same. Said fluid passage 25 is completely closed at its upper end by said bottom wall 12^a except for the bore 24. Said fluid passage 25 is adapted to open into and have communication with 10 a suitable pipe or conduit (not shown) the end of which is inserted into said passage. As shown, the wall of said passage 25 is provided with internal screw threads adapted to receive similar external screw-threads 15 on the end portion of such pipe.

The cylindric end portion 21 of the valve stem 20 extends downward through, and is adapted to slide endwise in said bore 24. The length of said stem 21 is such that its 20 lower end extends into said fluid passage 25 when the movable valve member 18 rests on said seat 23. In the vertical or upward and downward movement of said movable valve member 18, the stem 21 thereof slides or moves 25 endwise in said bore 24. Said stem 21 fits snugly, yet slidably, in said bore 24, so as to prevent leakage between such parts. As shown in Fig. 1, the valve stem 20 is provided with an axial or longitudinal passage 30 26 closed at both ends. Said valve stem is provided between its head 19 and shoulder 22 with a lateral outlet port 27 opening at its outer end into the valve chamber 15 and at its inner end into the longitudinal passage 35 26. Said outlet port 27 establishes communication at all times between said longitudinal passage 26 and said valve chamber 15. Said valve stem is further provided between its lower end and shoulder 22, 40 with a lateral inlet port 28 opening at its inner end into said axial passage 26 and at its outer end through the cylindric wall of said valve stem 21 and provides at certain times communication between said longitudinal passage 26 and the fluid passage 25. 45 When the movable valve member 18 is in the position shown in Fig. 1, the same rests on the seat 23 and the inlet port 28 is below the lower margin of the cylindric bore 24. 50 In such position of the parts, the inlet port 28 opens into the fluid passage 25, and communication is established between said passage and the valve chamber 15. On the other hand, when the movable valve member 18 55 is raised upward a sufficient distance to bring the inlet port 28 entirely above the lower margin of and within the cylindric bore 24, said inlet port 28 is closed by the cylindric wall of said bore and communication is cut 60 off between the fluid passage 25 and the valve chamber 15. As illustrated, the longitudinal or axial passage 26 is closed at its lower end by a screw or other plug 29.

Located between the valve casing parts 65 11 and 12, is a horizontal, flexible diaphragm

30. The latter is clamped into position between such parts by said clamp bolts 13, 13 which extend through suitable holes in said diaphragm. The valve chamber 15 opens upwardly through the top wall of said 70 part 12 and said diaphragm extends over and closes such opening. The central portion of the diaphragm is, therefore, opposite the seat 23. The head 19 of the movable valve member 18 bears upwardly against 75 said diaphragm 30. As shown, said head 19 is circular in form and is provided with a marginal annular flange 31, which has vertical sliding engagement with the wall surrounding the opening in the top wall of said 80 valve casing part 12.

The upper valve casing part 11 is provided with a chamber or recess 32, the latter opening downward through the bottom wall of said part 11. As shown, said diaphragm 85 30 extends over and closes the lower open end of said chamber 32. Located in said chamber 32 is a helical spring 33 which bears at its lower end against an annular member 34, the latter being in said chamber and resting upon the said diaphragm 30. Said annular member 34 is provided with an upwardly extending annular marginal flange 35 which forms with the body of said member 34 an upwardly opening socket in which 90 the lower end of the spring 33 is located. Said annular flange 35 bears against the side walls of the chamber 32, and guides the member 34 in its vertical or upward and downward movement, under the expansive 100 action of said spring 33 and the influence of the variations of pressure in the valve chamber 15. At the base of and surrounding the flange 35, is an annular, upwardly facing shoulder 36, adapted in an excessive 105 upward movement of the annular member 34 to come into contact with a fixed, downwardly facing, stop shoulder 37 within the chamber 32. When such parts are in contact, the member 34 is held against further upward movement. The upper end of spring 33 bears against an annular member 38, which fits loosely and slidably within said chamber 32. Said member 38 is provided with a depending marginal annular 110 flange 38^a which forms with the body of said member 38, a downwardly opening socket in which the upper end of said spring 33 is located. In order to vary the tension of the spring 33, so as to increase the amount 115 of pressure it exerts on the diaphragm 30, and consequently on the movable valve member 18, or in other words, to increase or decrease the degree of pressure that the movable valve member 18 must overcome in order to raise and close, or partially close the inlet port 28, I provide an endwise adjustable member 39, which, as shown, has the form of a stem extending into the upper part 120 of the chamber 33, through a vertical open- 125

130

ing 11^a in said valve casing part 11 above said chamber 32. The upper end of said opening 11^a is closed by packing rings 11^c, through which said stem extends. Said stem 5 39 is provided below said packing rings with external screw threads 39^a adapted to engage internal screw threads 11^b in the wall of the opening 11^a. The lower end of said stem 39 extends into said chamber 32 and 10 bears downwardly against said annular member 38. The upper end of said stem 39 is provided, exterior to the valve casing, with a hand wheel 41, by means of which the stem 39 may be rotated to move the 15 same endwise downward to effect the compression of the spring 33 or, to move the same endwise upward to permit the spring to expand and lessen the downward pressure on the movable valve member 18. The 20 packing rings 11^c are held tightly compressed, one against the other, to prevent leakage therebetween and the stem 39 by a screw cap 40 and an interposed washer 40^a.

Located in the valve chamber 15 is a helical spring 42, the latter surrounding the stem of the movable valve member 18 and bearing at its upper end against the head 19 and at its lower end against the seat 23. Said spring 42 under its expansive action, 30 tends to normally lift the movable valve member 18, and serves to counteract the downward pressure exerted thereon by the spring 33 located above the same.

The valve herein described and shown is 35 adapted in particular for use in a refrigerating apparatus, and in such a device, said valve acts to control and regulate the passage of the liquor or liquid ammonia from the low to the high pressure side of the valve. 40 It is upon the low pressure side of the valve that the liquid ammonia is converted into a gaseous form and in which form it becomes the refrigerating element. Said valve 10 is placed in a refrigerating apparatus with the 45 fluid passage 25 connected and communicating with the conduit or pipe leading from the liquor tank or condenser of the apparatus. The fluid passages 16, 17 are each connected and communicate with a conduit or pipe leading to the expansion coils in the 50 brine tank located in the chamber or compartment to be refrigerated. The ammonia when in liquid form, is maintained in such form under a high pressure and the passage 55 25 becomes the high pressure passage of the valve. A low pressure is maintained during the operation of the compressor in the valve chamber 15 and the communicating passages 16, 17 through the action of the compressor drawing the expanded ammonia gas from the valve chamber 15 into and through the 60 expansion coils. The valve chamber 15 and the communicating passages 16, 17 therefore, form the low pressure passages of the valve. 65 When the parts are in the position shown

in Fig. 1, the inlet port 28 is entirely below the lower margin of the bore 24 and said inlet port 28 is completely open and the liquor or liquid ammonia in the high pressure passage 25 escapes or flows therefrom into the 70 axial passage 26 in the movable valve member 18. The axial passage 26 communicates at all times with the valve chamber 15 and, it follows, that a low pressure is maintained in the same. As soon as a globule of liquid 75 ammonia enters said axial passage 26, it immediately flashes into a gas and enters, in such form, the valve chamber 15, through the outlet port 27. The flow of the liquid ammonia into the low pressure passage and 80 the conversion of same into gas is continued until the pressure in the valve chamber is raised sufficiently by the expanding fluid to overcome the downward pressure of the spring 33 and effect the raising or lifting of 85 the valve member 18 upward to bring the inlet port 28 above the lower margin of the bore 24 and thereby close, or partially close, the inlet port 28 and cut off the flow of the liquid ammonia into the valve chamber 15. 90 As the expanded gas is drawn from the low pressure passages into the expansion coils, the pressure in the low pressure passages is reduced. This permits the spring 33 to expand and move the movable valve member 95 18 downward to open the inlet port 28 wider and allow a re-flow of the liquid ammonia in the low pressure passages. By adjusting the stem 39, the downward pressure of the spring 33 on the movable valve member 18 100 may be regulated so that the latter will respond either quickly or be less sensitive to the variations of pressure in the lower pressure passages 15, 16, 17 of the valve. In other words, the pressure of the spring 33 105 may be so adjusted that the valve member 18 will not move the inlet port 28 into a completely closed position until a predetermined pressure is attained in the chamber 15. This, the inlet port 28 will be partially open 110 during degrees of pressure in the valve chamber 15 between normal and predetermined, or that degree of pressure under which the inlet port will be completely closed. It follows, that as the pressure in 115 the low pressure passages is increased above normal, the movable valve member 18 will be moved gradually upward and effect a gradual closing of the inlet port 28. Likewise, as the pressure in the low pressure passages is being reduced to normal, the valve member 18 descends gradually and effects a gradual opening of the inlet port 28. Consequently, the flow of liquid ammonia into the low pressure passages is gradually cut 120 off as the inlet port closes and is gradually increased as the same opens. The spring 42 counteracts the downward pressure of the spring 33 and serves to prevent a sudden and 125 quick downward movement of the valve 130

member 18. Should the excess pressure in the valve chamber 15 be relieved before the inlet port 28 is completely closed or entirely above the lower margin of the bore 24, the 5 movable valve member 18 will immediately move downward to further open said port 28. Manifestly, the valve 10 is automatic in its action and under variations of pressure controls the admittance of the liquid ammonia into the low pressure passages of the 10 valve.

As illustrated (see Fig. 3), the inlet port 28 is elongated lengthwise of the valve stem 20. The ends of said port merge off, in a 15 sense, into a point, so that the lower end of the inlet port 28 is narrower laterally than the port at its center. This insures a gradual lessening of the size of the opening afforded by the port 28 in the closing of the 20 inlet port, and a gradual widening or increasing of the size of said port 28 in the opening of the same.

The inlet port 28 is located at one point only circumferentially of the valve stem and 25 opening outwardly at such point through the cylindric wall of said valve stem. Said inlet port 28 is of such narrow dimensions laterally, or in a direction circumferentially of the valve stem, that the opening afforded 30 for the passage of the liquid ammonia, is substantially such as that formed by a circular aperture. By reason of this fact, when the inlet port 28 is only partially below the lower margin of the bore 24, the opening 35 for the passage of liquid ammonia is only partially open and just enough liquid flows into the low pressure passages as will be readily converted into a gaseous form. Flooding of the low pressure passages 15, 40 16 and 17 is, therefore, prevented. When the inlet port 28 is moved entirely below the lower margin of the bore 24, the inlet port is open to its fullest extent and affords a full passage for the liquid ammonia. Said 45 inlet port 28 is completely and fully open, only, when the valve stem is moved endwise downward to the lower limit of its downward movement. Any endwise movement of the valve stem short of a full downward 50 movement thereof, will not effect a complete opening of said inlet port 28. Any endwise movement of the valve stem between the positions when the inlet port 28 is completely closed or opened will effect only a 55 partial opening of said inlet port. Manifestly, the endwise movement of the valve stem between the fully closed and opened position of the inlet port 28 insures a degree of control of the passage of liquid ammonia 60 into the low pressure passages that is automatically controlled and regulated accurately. The opening afforded by the inlet port 28, as the latter is moved upward under the variations of pressure in the low 65 pressure passages is decreased in size and

area and the amount of liquid ammonia that flows into the low pressure passages is proportionate to the size of the opening afforded for the passage of the liquid and the pressure required. In the downward movement of the inlet port 28 the opening afforded by the latter is increased in size as the stem moves downward and the flow of liquid into the lower pressure passages is increased proportionate to the increasing size of the 75 opening. Such would not be the case, should the valve stem be provided with an outwardly opening annular groove encircling said stem and opening into fluid passages through the valve stem, as such fluid passages would be fully and completely open when the peripheral groove is moved only partially below the lower margin of the bore. It follows, that with a peripheral groove, the size of the opening afforded by the fluid 80 passages is not changed in the endwise movement of the valve stem and as a result, the low pressure passages are likely to be flooded as the amount of liquid that flows into the low pressure passages is constant no matter 85 how far the groove extends below the lower margin of the bore. The inlet port 28 is smaller in transverse area than the like area of the outlet port of the movable valve member. 95

The fluid passage 26 being within the walls of the valve stem, the passage afforded for the liquid ammonia from the high to the low pressure passages of the valve is not between the valve stem and the walls 100 of the cylindric bore.

The bottom wall of the valve chamber 15 constitutes the fixed valve member and the valve member 18, the movable valve member 105 of the valve 10.

In Fig. 4, I have shown the movable valve member 18 provided with two lateral outlet ports 43, 44, both substantially alike in form and diametrically opposite each other. With two outlet ports, the gas enters the valve chamber 15 on opposite sides of the valve stem and the pressure against the valve stem is on opposite sides thereof. This insures a balancing of the valve 18 as the stem thereof is not forced against but one side of the 110 bore 24. Thus, an uneven wearing of the parts is prevented.

A fluid pressure or expansion valve embodying the features of my invention may be variously modified with regard to its details of construction and arrangement of parts and I do not desire to be limited to the specific details and arrangement of parts herein illustrated and described, except in so far as is pointed out in the appended 115 claims. 120

I claim as my invention:

1. An expansion valve adapted for use in a refrigerating system, comprising a valve casing having high and low pressure pas- 130

sages, a fixed valve member interposed between said passages and separating one from the other, a movable valve member provided with a stem having sliding engagement with said fixed valve member, said stem being provided with an axial passage closed at both ends and having an outlet port establishing communication between said low pressure passage and said axial passage, said stem having an inlet port adapted to establish communication between said high pressure passage and said axial passage, said inlet port coacting with a margin of said fixed valve member in the endwise movement of said movable valve member, so that endwise movement of the latter will effect the opening and closing of said inlet port, said movable valve member being subject to the pressure in said low pressure passage in a direction to shift said movable valve member into its closed position, and means acting on said movable valve member in opposition to the pressure exerted thereon.

2. A valve of the character described, comprising a valve casing having inlet and outlet passages, a fixed valve member interposed between said passages and separating one from the other, said fixed valve member being provided with a bore, a movable valve

member located above said fixed valve member and having a stem slidably mounted in said bore, said stem being provided with an axial passage closed at both ends and having an outlet port located above said fixed valve member and establishing communication between said axial and outlet passages, said stem being provided with an inlet port opening into said axial passage and being moved above and below the lower edge of said bore in the endwise movement of said movable valve member, a flexible diaphragm located above and in contact with said movable valve member, a spring above and bearing downward against said diaphragm, a spring surrounding said stem and bearing at one end against said movable valve member and at the other end against said fixed valve member, and means for varying the tension of said first named spring.

In testimony, that I, BENJAMIN S. McCLELLAN, claim the foregoing as my invention and affix my signature in the presence of two witnesses, this 31st day of December, 1914.

BENJAMIN S. McCLELLAN.
